FACE PLATE FOR A LIQUID GAGE

John D. Stacey, 1326 S. Devon Road,
Springfield, Mo. 65804

Filed June 18, 1969, Ser. No. 17,756

Term of patent 14 years

Int. Cl. D10—99

U.S. Cl. D52—6

FIG. 1

FIG. 2

FIG. 1 is a front elevation of a face plate for a liquid gage showing my new design; and

FIG. 2 is a rear perspective thereof.

The broken lines are shown for illustrative purposes only and do not form part of the claim.

I claim:

The ornamental design for a face plate for a liquid gage, as shown and described.
